F. MANKEY.
OPENWORK PANEL.

No. 18,451.

Patented July 10, 1888.

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 18,451, dated July 10, 1888.

Application filed February 22, 1887. Serial No. 229,266. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

My design consists in the open-work panel having the following configuration: I show first a series of openings, 1, each of which is bounded on opposite sides by reversely-curved edges A and B. Immediately adjacent to said curved portions are short straight portions C, D, E, and F. On opposite sides of said openings are the inwardly-curved portions G, H. The curved portion G is between the straight portions C and D, and the curved portion H is between the straight portions E and F. The openings 1 having this configuration are in a

regular row. Parallel to the row of openings 1 is another row of openings, 2, of the following configuration: The edges on two opposite sides of each opening show each two curves meeting, as I J and K L. The edges of each of the other sides of each opening show an inwardly-curved portion, M, straight portions N, and straight portions O at right angles to said straight portions N. The curved portions I, J, K, L are adjacent to the straight portions N. The rows of openings 1 appear alternating with the rows of openings 2.

I claim—

The design for an open-work panel, substantially as herein shown and described.

FREDERICK MANKEY.
